WILSON P. HUNT, CLARENCE W. HALLENE, AND SAMUEL L. BRANDENBURG, OF MOLINE, ILLINOIS, ASSIGNORS TO MOLINE TOOL COMPANY, OF MOLINE, ILLINOIS

GRINDING MACHINE

Application filed February 4, 1928. Serial No. 251,906.

Our invention has reference to an improvement in grinding machines, and relates more specially to multiple honing or lapping machines, of that type which is set forth in the former application of said Wilson P. Hunt for Letters Patent of the United States, filed October 17, 1927, Serial No. 226,717. These machines include a series of grinding tools, each supported on the end of a spindle and 10 designed for operation in the bore of an engine cylinder or similar piece of work. It frequently happens that the axial line of the cylinder and that of the spindle do not true up exactly, calling for a little variation of 15 the position of the grinding tool with relation to its support. This has been usually secured by means of a universal joint or other flexible connection between the spindle and tool, permitting a certain amount of flexibility to the action of the tool and enabling it to 20 adapt itself readily to its work. One of the purposes of the present invention is to provide a rigid support for the grinding tool, but have the tool itself, or the grinding element thereof, independently supported, so as 25 to be capable of instant and automatic adjustment and adaptation to the walls of the cylinder in which it is operating.

The invention includes a grinding mechanism in which the grinding elements are 30 capable of being expanded by means of a cone and pin arrangement, and another purpose of the invention is to have the cone member suspended in the end of a rigid mounting, so as to be permitted a limited shifting action independent thereof. By the present 35 construction and arrangement of the device there is a considerable saving in the cost of production thereof, through the elimination 40 of the universal joints or other special connections above referred to.

The improvements hereinafter set forth pertain to each of the unitary grinding mechanisms of a multiple machine, and the same will be shown and described herein in its relation to one of such units.

In the drawings:

Fig. 1 is a general elevational view of a mechanism including the invention, with the 50 upper part in vertical section.

Fig. 2 is a vertical section of the grinding tool on the broken line 2—2 of Fig. 3.

Fig. 3 is a cross-section, on the broken line 3—3 of Fig. 2.

The reference number 1 indicates a housing, comprising part of a general machine, in which is rotatably mounted a spindle 2, driven by means of gearing indicated at 3 and 4. Fixed in the lower end of the spindle is an extension 5, on the lower end of which is a cylinder 6, provided with pairs of wings 7, forming vertical channels 8. Supported in said channels are frames 9, by means of pairs of pins 10 and 11, extending inwardly through bearings 12 in the cylinder. The inner ends of the pins bear against cones 13 and 14 on a cone member 15 supported in the cylinder 6, and limited in its lateral movements therein by guides 16, adapted to bear against the inner wall of the cylinder. The frames 9 are held normally in their innermost positions, as shown in the drawings, by means of coiled springs 17 passing round the ends of the frames, and engaged by recesses 18 therein.

For use in the grinding operation each of the frames 9 is fitted with a stone 19 of abrasive material, the outer faces of which stones are spaced from each other a suitable distance to enable the same to be used in a bore of a specified size.

Supported in the spindle 2 is a rod 20, the lower end of which bears against the cone-member 15 or against a ball 21 in the upper end of said member, and overcoming frictional action between the rod and cone member. Upon the rod 20 being forced downwardly the movement thereof is imparted to the cone member, causing the cones 13 and 14 to move downwardly, forcing the pins 10 and 11 outwardly, and expanding 85 the frames 9 and grinding elements held thereby. By the use of mechanical means, such as is indicated in part at 24, this expansion can be made a gradual one, progressing as the honing operation proceeds, and the diameter of the bore increases. The rod 20 is held normally in an elevated position, and is returned thereto after being lowered, by means of a coiled spring 22 in a chamber 90 in the upper part of the spindle 2, and bear-

ing against a pin 23 in the rod. Upon the downward pressure upon the rod 20 being relieved the cone member is returned to an elevated position by the force of the pins 10 and 11 against the cones, induced by the springs 17.

Instead of being formed to fit snugly in the cylinder 6 the guides 16 of the cone member are spaced a little from the walls thereof, permitting a slight shifting of the grinders to one side or the other, and permitting the same to adapt themselves exactly to the work in which they are engaged. The spacing of such parts is somewhat exaggerated in the drawings, to more clearly illustrate the same. This eliminates any danger of the bore of a cylinder being ground too much on one side, and at the same time there is a uniform amount of wear on the grinders, by reason of the fact that they operate at all times with their faces in parallel relation with the axial line of the cylinder.

It will be understood that the connection between the spindle 2 and extension 5 is of a rigid character, so that the rotation of said parts is on the same axial line throughout, the only side play at the lower end thereof being in the cone member and grinder supporting frames. In fact, in some adaptations the spindle could be of a continuous tubular formation. The tool can also be provided with a single cone device, and other changes can be made in the construction and arrangement of the parts, without departing from the spirit of the invention, as set forth herein.

What we claim, and desire to secure by Letters Patent, is:

1. In a device of the class described, a housing, a spindle rotatably mounted therein, and provided with a cylinder on one of its ends provided with external longitudinal channels, a cone member supported in said cylinder, and having a clearance from the sides of the cylinder permitting a limited lateral flexibility of the cone member, frames in said channels capable of radial expansion, contact members connected with said frames in engagement with the cones of said cone member, means for holding said frames under inward tension, and means for moving the cone member to actuate said frames.

2. A device of the class described, comprising a tubular member rotatably mounted, and provided at one of its ends with longitudinal channels, frames supported in said channels and provided with pins extending into said tubular member, a cone device suspended on said pins in said tubular member, and spaced therefrom so as to be capable of a limited side play therein, and means for holding said frames yieldably in their innermost positions.

3. A device of the class described, comprising a tubular member rotatably mounted,

frames mounted on the end of said tubular member so as to be radially movable, and adapted for the support of grinding elements, a double cone member in said tubular member and spaced therefrom so as to be capable of a limited side play therein, connections between said cone member and said frames serving as supports for the cone member, and operable thereby to cause the expansion of said frames, means for holding said frames yieldably against the action of said cone member, and means for imparting a movement to said cone member longitudinally of the tubular member to suitably expand said frames.

4. A device of the class described, comprising a spindle rotatably mounted, a tool head on one end thereof having external frame guides, frames supported in said guides so as to be radially expandable, a cone member in said tool head of slightly less diameter than the bore of said head and capable of a limited side play therein, pins carried by said frames in contact with said cone member and operable thereby to spread said frames, means for holding said frames yieldably against the force of said cone member, a rod carried by said spindle, bearing against said cone member, and capable of imparting movement thereto to actuate said frames, and means for holding said rod normally without pressure on said rod.

In testimony whereof we affix our signatures.

WILSON P. HUNT.
CLARENCE W. HALLENE.
SAMUEL L. BRANDENBURG.
